UNITED STATES PATENT OFFICE.

LEWIS S. HOYT, OF BOSTON, MASSACHUSETTS, ASSIGNOR TO ALBERT G. SMALLEY, OF SAME PLACE.

STOPPLE-RECEPTACLE.

SPECIFICATION forming part of Letters Patent No. 315,504, dated April 14, 1885.

Application filed January 5, 1885. (No model.)

To all whom it may concern:

Be it known that I, LEWIS STEBBINS HOYT, a citizen of the United States, residing at Boston, in the county of Suffolk and State of Massachusetts, have invented a new and useful 5 Elastic Receptacle and Pull for Stopples, of which the following is a specification.

The object of my invention is to provide an outer covering or receptacle constructed and 10 arranged to contain, preferably, imperfect stopples, united with a strengthening-bar to impart inflexibility and give them an appreciable commercial value.

To carry my invention into effect, I produce 15 a receptacle from thin caoutchouc, molded and vulcanized to conform to the general shape of the stopple it is designed to cover, and of the various dimensions required.

In the manufacture of said receptacle care 20 is employed to produce a uniform thickness and density of material, being made sufficiently thick to withstand the attrition of the earthen or glass wall of the vessel's neck. Through the top of said receptacle a circular opening is formed, 25 central in its upper diameter, for the admission of the stopple in the act of covering.

It will be observed when assorting the receptacles a size smaller than the cork or stopple designed to cover should be selected, that 30 the contraction of the receptacle may compress uniformly all portions of the exterior of said stopple after the same is inclosed.

To facilitate the withdrawal of the stopple from the neck or mouth of the vessel, a "pull" 35 is attached, in its aggregations comprising an eyebolt, a convex circular centrally-perforated cover or washer, and a double circular lifting-ring. In connecting said pull to its stopple, the eyebolt is first thrust from the top longitudinally through said stopple downward, where its end is bent at an acute angle to form 40 a secure "holdfast." The receptacle is now drawn over the stopple, and the cover is then placed over the eye and pressed firmly down, 45 so that the eye shall penetrate the slotted aperture and rest on a level with the lower inner circular circumference of said eye, its overlying flanged periphery resting upon and 50 confining the edge of the circular opening in the receptacle. At this stage the double lift-

ing-ring is placed through the eye and rotated until the position of said eye is between the abutting ends of the ring. The purpose, primarily of said pull is to withdraw the stopple; but it subserves also to strengthen and impart a degree of rigidity, which is an important factor not found in the class of imperfect cork stopples for which my invention is more particularly designed, the obvious advantages of which are more readily determined by referring to the drawings, forming a part of this specification, in which—

Figure 1 exhibits in perspective my improved invention inclosing a stopple with its attachments complete. Fig. 2 shows a longitudinal central section through receptacle, ring, cover, and stopple with bar in elevation. Fig. 3 shows the method of forming and cutting the lifting-rings. Fig. 4 is a side elevation of the elastic receptacle in part section 65 to exhibit its interior. Fig. 5 is a perspective view of the aggregate devices comprising the pull. Fig. 6 is a view in perspective of the double lifting-ring.

Similar letters of reference indicate like parts in the various views thereof.

A is the receptacle, of caoutchouc, inclosing a stopple. B is the top provided with the circular expansive opening C for the admission of the stopple D. E indicates the perforated convex cover, and F designates the binding periphery. G is the strengthening-bar, with its lower end or point, H, turned at an acute angle, to prevent its straightening when force is employed to withdraw the stopple from the vessel. I is the head of said bar, formed into an eye to receive the double lifting-ring J. In the formation of said ring a wire of suitable size is closely coiled in desired lengths. The coils are then severed, as shown in Fig. 3, so that the cut ends K K very nearly abut, and acting against each side of the bolt-head I when in position serves to confine said ring in its place, preventing rotation.

Having fully described my invention, what I desire to secure by Letters Patent and claim is—

1. The receptacle A, having converging or parallel sides forming a chamber, b, for the reception of a stopple, in combination with the

aggregate devices E J G, constituting the pull, substantially as and for the purpose described.

2. In a flexible stopple-receptacle, the combination of the perforated convex annular 5 flanged cover E, confining the circular elastic edge of the receptacle-orifice C, the double lift-ring J, and right-angled strengthening-bar G, whose circular head I doubly operates to receive said double ring and to oppose the several ends K of the same to prevent its rotation, substantially for the purpose specified.

3. In a stopple-receptacle, the combination of a convex perforated binding-cover, E, and bar G with the double lifting-ring J, having 15 opposing ends K K, abutting against each side of the bolt-head I, substantially as described.

4. In combination with an open-topped elastic chambered stopple-receptacle, the double lifting-ring J, the perforated annular flanged convex cover E, and strengthening-bar G, all 20 operating as and for the purpose herein set forth.

In witness whereof I have signed this specification in presence of two subscribing witnesses.

LEWIS S. HOYT.
